UNITED STATES PATENT OFFICE.

BENNIE GOODMAN, OF MILLICAN, OREGON.

FOLDING AIR-PUMP.

1,241,959.

Specification of Letters Patent.

Patented Oct. 2, 1917.

Application filed November 23, 1916. Serial No. 133,020.

To all whom it may concern:

Be it known that I, BENNIE GOODMAN, a citizen of the United States, residing at Milligan, in the county of Crook and State of Oregon, have invented certain new and useful Improvements in Folding Air-Pumps; and I do declare the following to be a full, clear, and exact description of the invention, such as will enable others skilled in the art 10 to which it appertains to make and use the same.

My invention has reference to air pumps in general and more particularly to those designed primarily for inflating automobile 15 tires.

The object of the invention is to provide a simply constructed and inexpensive pump of this class which may be compactly folded for carrying in the vehicle body and set up 20 for use with little trouble.

With this general object in view, the invention resides in certain novel features of construction and in unique combinations of parts to be hereinafter fully described and 25 claimed, the descriptive matter being supplemented by the accompanying drawings which constitute a part of this application and in which:

Figure 1 is a side elevation of a pump 30 constructed in accordance with the invention;

Fig. 2 is a top plan view thereof;

Fig. 3 is an end elevation;

Fig. 4 is a vertical longitudinal section on 35 the plane of the line 4—4 of Fig. 3.

Fig. 5 is a top plan view of the pump in folded position;

Fig. 6 is a detail sectional view through the bearing at the top of the bracing rod.

40 In specifically describing the structure shown in the drawings above briefly described, similar characters will be employed to designate corresponding parts throughout the several views and reference will be 45 herein made to the numerous elements by their respective indices. To this end, the numeral 1 designates a flat rectangular elongated base plate to one end of which a pair of pump cylinders 2 are pivoted as indicated 50 at 3.

The usual pistons 3' are disposed in the cylinders 2 and are secured to the inner ends of the pump rods 4, the outer ends of said rods being pivoted to the outer ends of a 55 pair of crank arms 5 which project in op-

posite directions from a shaft 6. One of the arms 5 is rigidly secured to its respective end of the shaft 6 while the other is held on the other end of said shaft by means of a pin 7, removal of said pin permitting the 60 two handles to extend in the same direction from the shaft 6 when the device is folded as depicted in Fig. 5. The outer ends of the crank arms 5 are equipped with handles 8 which are preferably pivoted at 9 so as to 65 permit them to fold compactly toward the arms 5.

The shaft 6 is rotatably mounted in a bearing 10 carried by the upper end of a standard 11 preferably formed of channel 70 iron or steel, the lower end of said standard being hinged at 12 to the base 1 between the pivots 3. An inclined brace 13 is pivoted at one end to the standard 11 as shown at 14 and the other end of said brace is hinged at 75 15 to a flat rectangular foot plate 16 which rests on the base 1 either when the pump is in use or when said pump is folded for carrying within the machine or storage in any compact space. 80

The two pump cylinders 2 may be provided with any suitable means for conducting compressed air therefrom to the vehicle tires or to other points at which it is to be utilized, but two separate tubes 17 preferably lead from the lower ends of said cylinders to a coupling 18 by means of which they are connected to a common delivery tube 19, which tube may be provided on its end with any preferred means for attaching it to the 90 valve of a tire. 95

When the improved pump is not in use, the foot plate 16 is folded under the brace 13 and both cylinders 2 are then moved downwardly until they overlie the base. 95 Previous to this operation, however, the handles 8 are folded and the cranks 5 are brought into close relation by removing the pin 7. With the numerous parts folded in this compact manner, the entire device may 100 be carried in little space and if desired may be housed within a rectangular metal box not shown.

When the pump is to be used, it is set up as shown in Fig. 1 and the operator will 105 then place one or both feet on the foot plate 16 to hold the brace 13 in operative position to cause the latter to prevent vibration of the standard 11. Rotation of the cranks 5 by means of the handles 8 will now recipro- 110

cate the rods 4 to cause the pistons 3' to compress air in the lower ends of the cylinders 2, said pistons discharging such air into the tire or other container in which it is being forced. Due to the fact that the rods 4 are pivoted to the cranks 5, they must necessarily oscillate as well as reciprocate, this movement being permitted by the pivots 3 of the cylinders 2, which pivots allow said cylinders to oscillate as the cranks are rotated.

From the foregoing taken in connection with the accompanying drawings, it will be seen that although the improved device is extremely simple and may be marketed at a minimum price, it will be highly efficient and durable. For these reasons, the construction shown and described constitutes the preferred form of the device but it is to be understood that within the scope of the invention as claimed, numerous changes may be made without sacrificing the principal advantages thereof.

I claim:

1. In combination a base, a pump pivotally mounted on said base for downward folding, means for operating said pump, a standard upon which said operating means are mounted, said standard being hinged to said base for downward folding, a brace pivoted to said standard for holding the same in upright position and a foot plate carried by the lower end of said brace and adapted to be held against the upper side of the base by the operator's foot.

2. A structure as specified in claim 1, said foot plate being pivoted to said brace to permit compact folding thereof.

In testimony whereof I have hereunto set my hand in the presence of two subscribing witnesses.

BENNIE GOODMAN.

Witnesses:

DORA A. JOHNSON,
ALMA KELLER.
